UNITED STATES PATENT OFFICE.

ARTHUR WILLIAMSON GREENE, OF RICHMOND, VIRGINIA.

AUTOMATIC REGULATOR.

1,331,867.

Specification of Letters Patent.

Patented Feb. 24, 1920.

Application filed January 22, 1917. Serial No. 143,796.

To all whom it may concern:

Be it known that I, ARTHUR W. GREENE, a citizen of the United States, residing at Richmond, in the county of Henrico, State 5 of Virginia, have invented certain new and useful Improvements in Automatic Regulators; and I do hereby declare the following to be a full, clear, and exact description of the invention, such as will enable others 10 skilled in the art to which it appertains to make and use the same.

This invention relates to regulators for condition controlling devices such as are used for controlling conditions in various 15 machinery and processes, as for instance, the controlling device for controlling either or both of the draft conditions and stoker conditions in a boiler furnace so that the boiler pressure is controlled.

20 In devices of this character heretofore used, where electrical control has been attempted the usual expedient has been to operate a controlling device when the condition exceeded a predetermined maximum or 25 fell below a predetermined minimum by closing an electric circuit. The difficulty with existing devices of this description has been that the controlling device could not be caused to operate with sufficient delicacy 30 to instantly restore the conditions which had varied from abnormal to the normal conditions. For instance, it has been common to control furnace dampers by closing a circuit through pressure actuated means. This circuit operates, in the usual construction, a 35 motor which opens or closes the damper. Experience has shown that when a boiler, under these conditions, starts to increase its pressure, as for instance when part of the 40 load is thrown off, the increase of pressure will not stop at the maximum limit but will exceed that limit considerably. Now with the ordinary construction as above noted the motor will actuate continuously until the 45 damper is entirely closed. This cuts off the draft from the boiler furnace and the steam begins to decrease in pressure, which decrease in pressure swings over, due to the closed damper, to the minimum side but owing 50 to the closed damper does not stop at the minimum limit but swings greatly below the desired minimum. This pendulum like action takes place until the swinging has been reduced after which, if the external

condition, such as the load, be maintained 55 uniform, a better maintenance of the conditions in the boiler may be obtained.

One important object of the present invention is to provide an improved form of apparatus for regulating the condition controlling devices which is so arranged that the oscillations of the conditions due to surging beyond the desired maximum and minimum points are damped or checked in such manner that surging is entirely eliminated and in consequence a better adherence 65 to the desired normal condition is obtained.

Furthermore, in all regulators of this character heretofore used there is employed an element which varies in position between 70 limits, the variations being effected by variation of the condition to be controlled. To limit the movement of these elements, such as the hand of a pressure gage, a thermostat bar or the like, unduly stresses the movable 75 element.

Another important object of the present invention is to provide an improved form of regulator equipped with a moving element controlled by variation in the condition to 80 be controlled which moving element is capable of non-resisted movement beyond the desired limit of variation of such condition.

A third important object of the invention is to provide an improved form of regulator 85 for condition controlling devices and which employs an element variable with decremental and incremental differential variations of the condition to be controlled, the regulator being arranged to integrate these differential 90 variations so as to produce a step by step movement in the condition controlling device.

Where the ultimate condition to be controlled is that of pressure the devices at present in use employ either a piston movable 95 in a cylinder, or more generally an expansion cell, the usual type of which consists of a pair of diaphragms connected at their peripheries and having their centers movable, 100 one toward or away from the other according as the pressure decreases or increases. The first of these devices, the piston and cylinder, is open to the objection that it is practically impossible to maintain a tight fit between 105 the wall of the cylinder and the periphery of the piston. The second of these devices is open to the objection that the differential

variations in the condition to be controlled do not operate to produce a smooth and regular difference in distance between the centers of these diaphragms, but owing to the 5 inequalities inherent in such construction, the device controlled by the diaphragm will jump or jerk from one position to the other.

Experience has shown that there is but one device which will, without leakage, produce 10 a smooth and uniform movement of the actuating element of such a regulator as the present and this device is a Bourdon tube.

A further important object of the invention is to provide a regulator for condition 15 controlling devices wherein the actuating element of the regulator is operable by means of a Bourdon tube.

With the above and other objects in view, as will be hereinafter apparent the invention 20 consists in general of certain novel details of construction and combinations of parts hereinafter fully described, illustrated in the accompanying drawings, and specifically claimed.

25 In the accompanying drawings, like characters of reference indicate like parts in the several views, and:—

Figure 1 is a diagrammatic view of the 30 wiring connections used with one form of the invention.

Fig. 2 is a similar diagrammatic view of the wire and connections used with a second form of the invention.

Fig. 3 is a detail side elevation of a certain 35 switch used herewith.

Fig. 4 is a vertical section through said switch.

Fig. 5 is a front elevation of one preferred 40 form of circuit closer used herewith.

Fig. 6 is a side elevation of the circuit closer shown in Fig. 5.

Fig. 7 is a plan view of such a circuit closer.

Fig. 8 is a side elevation of a second preferred 45 form of circuit closer.

Fig. 9 is a detail section on an enlarged scale, the section being taken on the line 9—9 of Fig. 5.

Fig. 10 is a diagram of the contact rings 50 and the gaps in the cylindrical switch used in connection with the second form of the invention.

Considering now the general operation of the device as disclosed in the form shown in 55 Fig. 1 it will be observed that there is provided a pair of line wires 10 and 11 which receive their current from any suitable source of supply, the latter not being deemed necessary to be shown. One of these wires, as 10, 60 is connected by means of a wire 12 with the movable element 13 of the circuit closer, this element being controlled by the variations in the condition to be regulated or controlled.

For instance, where the condition to be controlled 65 is one of temperature the element 13

may be, if desired, a thermostat bar or may be a lever connected by suitable linkage to a thermostat bar. In other instances, as where the condition to be controlled is one of pressure, the element 13 may take the form of a 70 lever suitably pivoted and operatively connected to a Bourdon tube in order to afford smooth and uniform movement of this element under variations in the condition to be controlled due to variations in pressure. It 75 will be obvious that various other ways for controlling the element 13 will suggest themselves, the manner of controlling this element being dependent on the character of the condition to be controlled. Adjacent that end 80 of the element 13 which has the greatest amplitude of movement there is provided a series of contact points 14, 15, 16 and 17 and fixed in the paths of these points are yieldable contacts 18, 19, 20 and 21, the contacts 14 85 to 17 and contacts 18 to 21 being so disposed that the contacts 14 to 17 will successively engage the contacts 18 to 21. Moreover, while in the present instance, there has been shown a series of but four sets of contacts 90 yet the number of contacts may be varied at will in accordance with the extent and character of the control desired.

The switch used herewith is in the form of an insulating drum 22 and surrounding this 95 drum adjacent one end is a conductor band 23. Also surrounding the drum partially, are other conductor bands 24, 25, 26 and 27 in each of which there is provided a gap 28, these last bands being each connected to the 100 band 23. Wires 29, 30, 31 and 32 are connected respectively at one end to the contacts 18, 19, 20, and 21 and at the other end to brushes 33, 34, 35, and 36, these brushes bearing respectively against the bands 24, 25, 26 and 27. Other brushes 37, 38, 39 and 40 bear against these bands 24 to 27 respectively at points spaced from brushes 33 to 36. These last-mentioned brushes are connected by wires 41 in multiple to a wire 42, lamps 43 being connected into the wires 41 respectively, and being used as indicators only and not necessary to the operation of the controller. 110

At 44 is a motor controlled, as hereinafter described by the switch and mechanically 115 connected to the shaft 45 of the drum by a gear train 46. Now, let us consider what takes place when the member 13 is actuated to successively close the contacts 18, 19, 20 and 21. In this connection it is to be noticed that the gaps 28 are spaced around the drum 22 so that no two of these gaps are in alignment longitudinally of such drum. If the left hand end of the member 13 in Fig. 1 moves upward it first closes the contact 18, 120 the contact 14 striking said contact 18. Then a circuit will be established from the line wire 10 through the wire 12, member 13, contact 14, contact 18, wire 29, brush 33, ring 24, ring 23, brush 49, wire 48, relay or coil 125 130

47, wire 50, back to wire 11, exciting relay, causing plunger 51 to rise making contact between contact 52, and contact 53, thus making circuit from wire 11, contacts 53, 52, 5 wire 54, wire 55, wire 67, to motor 44, which in turn will rotate the switch drum 22, until the gap 28 of the ring 24 comes opposite brush 33. Finger 33 rests on gap 28 and is not now connected with ring 23, thus breaking circuit established, and the motor will stop and consequently the movement of switch 22 will likewise stop. If now the arm 13 rises still further until the contacts 15 and 19 are brought into engagement, then 10 a circuit similar to that just described will be formed through the ring 25, ring 23, brush 49, wire 48, relay 47, wire 50, wire 11, and the switch drum 22 will be turned until gap 28 in ring 25 comes opposite the finger 15 24. The circuit will again be broken and the motor stopped. This continues throughout the remainder of the movement of the arm 13. Thus it is to be noted that the differential movement of the arm 13 produced 20 by differential variations in the condition to be controlled will result in an integration of this movement by means of the switch so that the movement is caused to assume a step by step form upon gradual upward movement of the arm 13.

At 47 is a relay magnet which is connected by a wire 48 with a brush 49 engaging the ring 23. Furthermore, this magnet is connected by a wire 50 with the wire 42 and 25 consequently to the line wire 11. Thus whenever the member 13 is moved so as to close a circuit through one of the rings 24 to 27 a band circuit will be closed through the magnet 47 which will result in moving the 30 core 51 of this magnet to close a circuit through contacts 52 and 53, the contact 52 being connected by a wire 54 with a motor lead 55 while the contact 53 is connected to the wire 42 and thus to the line wire 11. 45 At 56 is a second motor lead which is connected by a wire 57 with the line wire 10.

In order to reverse the movement of the controlling device the member 13 is provided with an arrangement operative upon movement of said member in a downward direction, and although an integrated action would be preferably embodied in this arrangement, for the sake of clarity the bar 13 is provided in the present instance with a 50 single contact point 58 which is adapted, when said member 13 moves away from the contact 18, to engage a contact 59 which is connected by a wire 60, ring 60' (return limit), wire 60 with relay magnet 61, the 55 other end of the magnet winding being connected to the wires 42 and 11. This relay magnet controls contacts 62 and 63 and the contact 62 is connected to the wires 42 and 11 while the contact 63 is connected by a wire 64 with a motor lead 65. By this

means when the contacts 58 and 59 are brought into engagement current will flow through the magnet 61 and thus energize the leads 56 and 65. Condensers 66 are preferably connected in multiple between the wire 70 60 and line wire 10 and also between the ring 23 and line wire 10, as clearly shown.

Extending from the leads 55, 56 and 65 are motor connecting wires 67, 68 and 69. The motor is preferably a double field motor, the field windings being indicated respectively at 70 and 71 and the wire 67 is connected to the winding 70 while the wire 68 is connected to the winding 71, so that when current passes over the wire 67 the 75 motor will revolve in one direction and when current passes over the wire 68 the motor will revolve in the opposite direction. By means of this construction the motor may be caused through the varying of the conditions to be controlled, to revolve in one direction or the other and thereby actuate the switch in one direction or the other, an A. C. three phase motor may be used where reversal of rotation is desired, the relay switch 80 to motor being double pole cross connected, so as to give forward and reverse rotation as the case may be.

In the form of the device shown in Fig. 2, the line wires in which there is a pole 95 changing switch P are indicated respectively at 80 and 81. The line wire 80 is connected to the movable circuit closer 82 which carries contact points 83, 84, 85, and 86. In the paths of these contact points are arranged yieldable contacts 87, 88, 89 and 90, the contacts 83 to 86 and 87 to 90 being so arranged that movement of the bar 82 brings the contacts 83 to 86 successively into contact with the contacts 87 to 90, the latter 100 contacts being spring supported as in the previous case. Each of the contacts 87 to 90 has leading therefrom a wire 91 which is connected to one of a series of relay magnets 92, 93, 94 and 95, these magnets all being 105 connected in multiple by wires 96 to the line wire 81. Each of the magnets 92 to 95 is provided with an armature 97 which is normally held away from its magnet by means of a spring 98 pulling on an arm 99 110 attached to the armature and each armature is further provided with a dash-pot 100 for the purpose of rendering its movement steady and slow. Connected to the armatures 97 are contact arms 101, 102, 103 and 120 104. Each of the arms 101 to 104 oscillate between a pair of contacts 105 and 106. From the respective contacts 105 lead wires 107, 108, 109, and 110 which connect with respective fingers 111, 112, 113 and 114. 125 From each of the respective contacts 106 lead wires 115, 116, 117 and 118. These wires connect with respective fingers or brushes 119, 120, 121, and 122. The limit switch employed with the form shown in 130

Fig. 2 consists of an insulating drum 123 whereon is mounted a series of contact strips 124 whereon rests the respective fingers or brushes 111 to 114 and 119 to 122. The ends of each of these strips 124 are so spaced that one of each pair of the fingers or brushes as 111 and 119 will at all times rest on the strip 124. Moreover, all of the strips are connected by wires 124^a to a ring 125 and to a second ring 126. Bearing on the ring 125 is a brush or finger 127 which is connected by means of a wire 128 with a magnet 129, this magnet being one of the magnets of a double throw relay. In like manner the ring 126 has bearing thereagainst a brush or finger 130 which is connected by a wire 131 with the other magnet 132 of said double throw relay. Between the magnets 129 and 132 is located an armature 133 so that when the magnet 129 is energized the armature is drawn in one direction while, when the magnet 132 is energized the armature is drawn in the other direction. These magnets 129 and 132 are connected in multiple by a wire 134 to the line wire 80. The armature 133 carries a contact arm 135 which is connected by a flexible wire 136 with the wire 134. This contact arm 135 oscillates between contact points 137 and 138 so that when the magnet 129 is energized the arm 135 contacts with the contact 138 while when the magnet 132 is energized the arm 135 contacts with the contact 137. These contacts 137 and 138 are connected by wires 139 with motor leads 140 and 141, the lead 140 being connected to one field winding 142 of a motor 143 while the lead 141 is connected to a second field winding 144 of said motor, the motor being, like that in the first instance of the double field type. At 145 is the third or return motor lead which is connected by a wire 146 with the line wire 81. Bridged across between the wires 107 and 128 is a condenser 147 while a similar condenser 148 is bridged between the wires 115 and 131. Connected to the respective wires 107 to 110 are signal lights or other indicators as shown at 149 and these indicators are connected in multiple by a wire 150 to the line wire 80.

In order that several devices may be controlled by the same variation in conditions which is used to actuate the bar 82 the respective arms 102 to 104 may be provided with extra contact members 151 which engage contacts 152 and 153 similar to the contacts 105 and 106 and like them connected to a limit switch B which is precisely similar in all respects to the previously described limit switch which is distinguished by being indicated in general by the character A, the reference characters for the brushes and wires being indicated by the same numerals characterized by prime marks. For instance, the fingers are indicated respectively by 111', 112', 113', 114', 127', 119', 120', 121', 122' and 130'. The lead wires are of course indicated in like manner.

Moreover the arm 82 may be provided with the contact 154 which, under certain conditions engages a contact 155, the conditions being opposite those causing engagement of the contacts 87 to 90 respectively. It will be obvious that the number of contacts and their connecting parts may be increased or decreased from that shown and it will also be obvious that only selected relay magnets 92 to 95 need be utilized to operate any auxiliary apparatus. The contact 155 is connected by a wire 156 to a condenser 157 connected in turn by a wire 157' with the wire 150.

Furthermore the motor 143 is connected by a gear train 158 to the shaft 159 of the limit switch.

In order to illustrate how the device may be used to control or regulate a condition controlling device there has been shown in connection with Fig. 2 a flue 160 the passage of gas through which is controlled by a damper 161. Mounted on the stem of this damper is a wheel 162 whereto are connected the cords or wires 163 which are led around guide wheels or idlers 164 to a driving wheel 165 on one of the shafts of the gear train. In place of cords or wires sprocket chains may be employed and the wheels 162 and 165 may be sprockets. By this means when the gear train is actuated the damper will be moved from one position to the other as will be obvious.

Other apparatus has also been disclosed in this connection so that it may be seen that the device may be used for controlling all of the portions depending upon a given variable condition. For instance, there is shown in Fig. 2 at 166 an engine governor which is connected to a lever 167 having an adjustable fulcrum 168. Over the top of this sleeve is a shaft carrying a wheel 169 connected by wires 170 to a wheel 171 on the same shaft as the wheel 165. Rotating with the wheel 169 is a cam 172 which urges, when operated, the end of the lever 167 with which it contacts downward, this action being effected of course when the limit switch A revolves. In order to replace the lever, the cam returns to its original position, the engine governor forcing it to normal position and in order to increase speed of engine a slot is made in the cam at the normal position; the lever 167 to be raised farther, a wire 173 leads to a solenoid 174 having a core 175 connected to said lever 167, the solenoid being further connected by a wire 176 to the wire 81. By this means closing of contacts 154 and 155 will energize the solenoid and pull up on the core. Also the stoker may be started and stopped, the stoker being driven by a motor 177. To

supply power to this stoker line wires 178 are connected to a switch 179 to wires 180 and 181. The wire 181 is connected to a rheostat 182 which is operated by means of 5 a flexible cord 183 connected to a wheel 184 on the shaft with the wheels 165 and 171. This rheostat is also connected by a wire 185 to a manually operable rheostat 186 connected by a wire 187 through a variable 10 resistance switch 188 to the wire 181, the switch being also connected by a wire 189 with the motor 177. Thus rotation of the switch A will operate the rheostat 182 and consequently vary the speed of the motor 15 177 in a well known manner. Furthermore, the engine throttle 190 may be controlled independently of the governor 190^a through the medium of a lever 191 carrying a series of solenoid cores 192 connected to the lever 20 by pin and slot connections, there also being employed a solenoid core 193 likewise connected with the lever, the cores 192 being surrounded by the solenoid coils 194 connected by wires 195 with the wires 107' to 25 110' respectively, the cores also being connected by wires 196 in multiple to a wire 197 leading to the wire 150.

The core 193 is surrounded by a coil 198 connected by a wire 199 to the wire 156 30 and by a wire 200 to the wire 197. The arrangement of the cores is such that successive energization of the coils 194 from left to right will effect successive step by step movements of the lever 191 downward 35 while energization of the coil 198 will effect movement of the lever upward. In this form of the device, the operation follows closely the operation of the previously described form. As for instance, if the condition 40 is such that the bar 82 moves to close the contact 87 then the magnet 92 will be energized which will cause closing of the arm 101 onto the contact 105 and thus will establish a circuit from the line wire 80 to 45 the bar 82 through the contacts 83 and 87, the wire 91, the magnet 92 and wire 96 to the arm 101, from thence through its contact 105 and the wire 107 to the finger 111, to one of the bands or before-mentioned 50 rings 124, the circuit being thus continued through the wires 24^a and through the finger or brush 127 to the wire 128 so that the motor is driven in a forward direction. If the condition continues to vary in this same 55 direction then the contact 88 will be closed which will result in energizing the armature 93. If the condition does not continue to vary in this direction however the limit switch will be turned until the finger 111 60 comes opposite the break between the ring sections 124 when the circuit will be broken and the motor stopped. If the magnet 93 be energized as aforesaid then the circuit will be reestablished through the second 65 finger 112 and the motor operated again to

turn the limit switch through another arc. This will continue throughout the entire series of magnets 92 to 95. Supposing that when the magnet 93 has been energized conditions cease to vary in the direction to carry 70 the bar 82 upward in Fig. 2 and retrograde. Then as soon as this takes place and the contact between 88 and 84 is broken the magnet 93 will be deenergized with the consequence that the arm 102 will close a contact 75 with its contact 106 so that a circuit will be established through the finger 120 and the ring with which it engages. Under these circumstances the circuit passes out through the finger 130 and the motion of 80 the motor is reversed. The motor will continue to run in this direction until the finger 120 comes opposite the break between the two before-mentioned sections 124 of the limit switch whereupon the motor will cease 85 to operate. If conditions still continue to change toward normal then the magnet 92 will be deenergized with consequent closing of a circuit through the finger 119 to again 90 operate the motor and restore the limit switch to its original position. Thus, no matter whether the conditions vary from normal to a maximum or vary from maximum toward normal the operation of the condition controlling device will be step-by-step 95 operation, either upward or downward as the case may be. It will be obvious from further description of the operation that the motor 177, cam 172, solenoids for the lever 191, and the switch B will all be controlled in like manner.

In actual construction as shown on Fig. 5 and Fig. 6 it is preferred to mount the arm 13 on a bracket 201, which bracket is supported by a suitable base 202. The wire 105 12 is connected to a suitable terminal 202' on the base 202. Thus contact members 18 to 21, inclusive are in the form of screws, which are adjustably mounted on resilient arms 203, which extend outwardly from a bracket 110 204, which bracket is secured to the base 202, above the arm 13. These contacts are held in place by set screws 205. The contact member 39 is similarly mounted on a bracket 206. These brackets are provided 115 with a plurality of holes so that the number of resilient arms may be increased or decreased at will. Mounted on the base 202 is a Bourden tube 207, which is connected by means of a suitable pipe to a reservoir 208 to the upper end of which a pipe 209 is connected, leading directly to a boiler or other pressure organ. The reservoir 208 and the tube 207 are filled with water, so that the fluid pressure in the 120 pressure organ will exert pressure on the surface of the water in the reservoir 208 and operate the tube in the usual manner. Connected to the free end of the tube 207 is a connecting rod 210, which is made of 125 130

6

two pieces, the pieces being connected together by means of a turn buckle 211 preferably made of insulating material. This rod extends upwardly through the arm 13 and is slidable on a pin 212, which extends through a slot 213, in the rod. This pin is normally held in the lower end of the slot by coil springs 215, which are connected to the pins 212, and to the rod at 217. Pivotally mounted on the end of the arm 13, remote from the end on which the contacts are mounted, is a rod 218, on which a suitable number of weights 219 may be mounted. It will be obvious that, as the pressure on the water within the reservoir 208 increases, the arm 13 will be proportionately raised. The distance which it is raised, may be controlled by the turn buckle. For instance, if the device is to be used 20 in connection with a boiler of 180 pounds pressure, the length of the rod 210 will be regulated so that the arm 13 will rise the proper distance upon an increase of pressure on the boiler. Should it be desired to 25 increase the pressure necessary to raise the arm initially, this may be done by removing a weight from the rod 218, a number having been previously placed thereon, which weight will, of course bear a suitable relation to the lever.

In the embodiment of the invention shown in Fig. 9 of the drawing, I have illustrated a second Bourdon tube 220, which is connected to the cylinder of a pump and has its free end connected to the arm 13 by a rod 221, which is similar to the rod 210 and which is connected to the arm on the opposite side of the pivotal point 222 to that on which the arm 210 is located, the construction of this rod being similar to the construction of the rod 210. Thus the variation of pressure in the pump cylinder will cause the arm 13 to operate in the reverse manner than will the pressure in the boiler, being on the opposite side of the pivot, whereby tendency of failure of operation of the pump cylinder will procure an increased operation of the pump.

It will be noted that by reason of this particular construction of the Bourdon gage connection shown in Figs. 7, 8 and 9 the movement of the arm 13 is accomplished in a smooth and steady manner while at the same time the spring support of the stationary contacts affords means by which this arm 13 can move uninterruptedly beyond the limit desired, this being the limit at which the contact 18 is set. It will also be noted that by reason of this arrangement of contacts the differential movement of the arm 13 is integrated so that it is transformed into a series of step-by-step movements of the controlling motor.

It will be obvious that while this motor 65 has been shown as controlling a damper it

may be utilized to control any one of a large number of devices which act to control the conditions in a body, for instance, the regulator may be thermostatically controlled and thus control the conditions in a 70 chemical mixture to prevent excessive heat as in the manufacture of nitroglycerin and other explosives.

It will be noted that by obtaining the pressure, which actuates the Bourdon tube, 75 from a Pitot tube inserted in a pipe through which a fluid or gas is flowing under pressure, the condition control will be dependent on the product of the two variable quantities, namely pressure and rate of flow of 80 the liquid or gas in the pipe.

Having thus described the invention, what is claimed as new, is:

1. In a regulator for condition controlling devices, a series of normally open primary 85 circuits each including a fixed contact, a relay magnet, a circuit closing element movable into successive engagement with the fixed contacts, a series of normally open secondary circuits adapted to be successively 90 closed by the successive energization of the relay magnets, said secondary circuits including a relay having a magnet winding to which the secondary circuits are connected in multiple, a motor and normally open 95 circuit therefor closed by the energization of the secondary relay, and circuit breaker mechanism operatively connected to the motor and arranged to successively break the secondary circuits irrespective of the energization of the primary relays. 100

2. In a regulator for condition controlling devices, a series of normally open primary circuits each including a fixed contact, a relay magnet, a circuit closing element movable into successive engagement with said fixed contacts under the influence of changes in the condition to be controlled, a series of normally open secondary circuits adapted to be successively closed by the energization of said relay magnets, a series of normally closed secondary circuits adapted to be successively opened by the energization of said relay magnets, said secondary circuits including a relay provided with a pair 115 of magnets to one of which the first series of secondary circuits are connected in multiple and to the other of which the second series of secondary circuits are connected in multiple, a double wound motor arranged to 120 have a circuit closed through one of its windings by the energization of the first magnet of the secondary relay and to have a circuit closed through its other winding by the energization of the second magnet of 125 the secondary relay, and circuit breaker means, operatively connected to the motor and arranged to successively break the secondary circuits irrespective of the energization of the primary relays. 130

3. In a regulator for condition controlling devices, a series of normally open primary circuits each including a fixed contact, a relay magnet, a circuit closing element movable into successive engagement with the fixed contacts, a series of normally open secondary circuits adapted to be successively closed by the successive energization of the relay magnets, said secondary circuits including a relay having a magnet winding to which the secondary circuits are connected in multiple, a motor and normally open circuit therefor closed by the energization of the secondary relay, said secondary circuit including a rotary switch arranged to successively open the closed circuits, and a gear train connecting the motor and switch.
4. In a regulator for condition controlling devices, a series of normally open primary circuits each including a fixed contact, a relay magnet, a circuit closing element movable into successive engagement with said fixed contacts under the influence of changes in the condition to be controlled, a series of normally open secondary circuits adapted to be successively closed by the energization of said relay magnets, a series of normally closed secondary circuits adapted to be successively opened by the energization of said relay magnets, said secondary circuits including a relay provided with a pair of magnets to one of which the first series of secondary circuits are connected in multiple and to the other of which the second series of secondary circuits are connected in multiple, a double wound motor arranged to have a circuit closed through one of its windings by the energization of the first magnet of the secondary relay and to have a circuit closed through its other winding by the energization of the second magnet of the secondary relay, said secondary circuits including a rotary switch arranged to successively open the closed circuits, and a gear train connecting the motor and switch.
5. In a regulator for condition controlling devices, a series of normally open circuits, a rotatable switch drum, split bands on said drum having their ends spaced apart at different radial portions of the drum, a pair of contacts in each circuit engageable with the drum, switches in said circuits controllable by progressive difference of like char-
- acter in the condition to be controlled for successively closing said circuits, a motor included in said circuits, and a drive connection between the motor and switch drum.
6. In a regulator for condition controlling devices, a series of normally open primary circuits each including a fixed contact, a relay magnet, a circuit closing element movable into successive engagement with the fixed contacts, a Bourdon tube operatively connected to said element and to a part of the controlled system in which pressure conditions may vary, a series of normally open secondary circuits adapted to be successively closed by the successive energization of the relay magnets, said secondary circuits including a relay having a magnet winding to which the secondary circuits are connected in multiple, a motor and normally open circuits therefor closed by the energization of the secondary relay and circuit breaker mechanism operatively connected to the motor and arranged to successively break the secondary circuits irrespective of the energization of the primary relays.
7. In a regulator for condition controlling devices, a series of normally open primary circuits each including a fixed contact, a relay magnet, a circuit closing element movable into successive engagement with the fixed contacts, two Bourdon tubes operatively connected to said element and to parts of the controlled system in which pressure conditions may vary, a series of normally open secondary circuits adapted to be successively closed by the successive energization of the relay magnets, said secondary circuits including a relay having a magnet winding to which the secondary circuits are connected in multiple, a motor and normally open circuit therefor, closed by the energization of the secondary relay and circuit breaker mechanism operatively connected to the motor and arranged to successively break the secondary circuits irrespective of the energization of the primary relays.

In testimony whereof, I affix my signature, in the presence of two witnesses.

ARTHUR WILLIAMSON GREENE.
